UNITED STATES PATENT OFFICE.

GEORGE L. BADGER, OF QUINCY, MASSACHUSETTS, ASSIGNOR TO EQUITABLE AUTO-TRUCK POWER AND BURNER COMPANY, OF LYNN, MASSACHUSETTS, A CORPORATION OF MAINE.

APPARATUS FOR BURNING OIL.

SPECIFICATION forming part of Letters Patent No. 735,441, dated August 4, 1903.

Original application filed August 2, 1900, Serial No. 25,713. Divided and this application filed September 28, 1900. Serial No. 31,420. (No model.)

To all whom it may concern:

Be it known that I, GEORGE L. BADGER, of Quincy, in the county of Norfolk and State of Massachusetts, have invented a new and useful Improvement in an Apparatus for Burning Oil, of which the following, taken in connection with the accompanying drawings, is a specification.

My invention relates to an apparatus for burning hydrocarbon fluids; and it consists in the construction of the several parts, which may be better understood by reference to the drawings and specification, the object being to make a burner that will consume with perfect combustion ordinary kerosene-oil.

This application is a division of application Serial No. 25,713, filed August 2, 1900.

The invention is embodied in the mechanism shown in the accompanying drawings, in which—

Figure 1 is a vertical section through the burner. Fig. 2 is a horizontal section taken on line 2 2 of Fig. 1, the division-plate A⁶ being omitted. Fig. 3 is a horizontal section taken on line 3 3 of Fig. 1.

The base or lower part of the casing of my burner is indicated by A, provided with an annular wall A' A', to which is attached a plate A⁶ A⁶. Below this plate A⁶ A⁶ a series of perforations a a are made for the admission of air into the lower or sub compartment S, in which is located the mechanism for causing and controlling the mixing of air with the heated oil-vapor and also mixing-chambers

L and M, from which the oil-vapor and air pass through openings in the division-plate A⁶ to the concentric heating-chambers S' S' S² S²—that is, the space between the division-plate A⁶ A⁶ and the fire-plate B B' B B'. In these concentric heating-chambers S' S' S² S² the mixture formed in the lower chambers L and M becomes of such a nature as to be completely combustible previous to its passage through the perforated plate B B' B B' into the combustion-chamber S³.

Oil is drawn from any suitable source through the pipe C and made to flow through the coil C' C² to the pipe C³. Thence it passes downward to the horizontal pipe C⁴, Figs. 1

and 3, which delivers it in the form of vapor 50 through the small orifices E E E' E into the open cone-shaped injector-nozzles placed in multiple series, (see F F' F F', Fig. 3,) to which air is supplied at their mouths and also through the openings H H. As the commingled oil-vapor and air leaves the primary nozzles F F it passes into a second set of similar injector-nozzles F' F' and gathers additional air from the mouths of the second nozzles and also from the openings H' H'. The mixture 60 now flows through the contracted passages K² (which, in fact, constitute other injector-nozzles) into the induction-tubes K' K' K' K'. Thence the mixture passes from the tubes K' into the mixing-chambers L L, from which it 65 flows upward into the outer one S' of the concentric heating-chambers S' S². (See Figs. 1 and 2.)

The oil-vapor that jets from the orifice E' passes through injector-tubes similar in all 70 respects to those already described (F and F') into the induction-tube K³, which is like the tube K', already described, and discharges into the central mixing-chamber M and thence to the inner concentric heating-chamber S², 75 (see Figs. 1 and 2,) where the mixture becomes ready for complete combustion. The volume of vapor and air now being thoroughly mixed and heated to a high temperature passes through the perforations D and D' into 80 the combustion-chamber above the plate B' and immediately beneath the boiler or thing to be heated.

The combustion-chamber S³ is annular in horizontal section. The inner wall is shown 85 at A⁸ and the outer wall at A⁹. (See Figs. 1 and 2.) Both of the walls are perforated, as indicated by b b. A third wall A⁸ incloses the whole and is closed at the top by the plate A⁵ and at the bottom by a register device S⁵ 90 S⁶, so that the amount of air admitted to the space S⁴ and thence through the outer perforated wall A⁹ can be regulated or cut off altogether, as may be desired. The inner air-space S⁷ has a closed top and a register bottom V V', the movable part of which is operated by a lever V³ and any suitable connections. By the register devices just de-

scribed the inlet of air to the combustion-chamber S^3 may be regulated at will or entirely cut off.

The oil-vapor inlets $E E' E E$, Fig. 3, are 5 opened and closed by needle-valves $R R R' R R$, respectively. These needle-valves pass through protecting-tubes $N N$. The four needle-valves R are attached directly to the cross-bar R^3 and are operated by the lever R^9 , which is connected by the link R^8 to the bracket-piece A^7 and is adapted to actuate the bar R^3 through the sliding rod R^4 , head R^7 , and pivot R^{10} . The needle-valve R' is indirectly connected to the bar R^3 by means 15 of the short bar R^2 and steady-rods $r r$. The sliding rod R^4 rotates and is turned by the hand-wheel R^6 . Its longitudinal motion is limited by the collar R^5 between the arms of the bracket A^7 . Screw-threads $t t'$ are cut 20 upon the ends of the rod R^4 , the screw at one end being a right-hand one and at the other end a left-hand one, so that by turning the rod by the hand-wheel R^6 the distance between the head-block R^7 and the short bar R^2 and the attached needle-valve R' can be 25 adjusted—that is, the needle-valve R' can be so adjusted as to have the opening E' open after the other openings $E E' E$ are closed by their respective needle-valves $R R R R$. 30 By this device the flow of mixed vapor and air through the central tube K^8 to the chamber M and thence to the perforations $D' D'$ can be maintained after the flow through the tubes $K' K' K' K'$ to the chamber $L L$ and the 35 perforations $D D$ is cut off.

If desirable, the sliding part S^6 of the register device $S^5 S^6$ may be connected by the pivot T^8 , link T' , adjusting-nut T^2 , and link T to the lever R^9 , so that the air-supply may 40 be governed by the same lever that regulates the vapor-supply. This controlling device can be so adjusted that the air passing through the perforations $b b$ in the wall A^9 may be cut off entirely while the vapor mixture is burning and opened only when it is 45 desired to cool off the apparatus, or any other desirable adjustment may be made to adapt the burner for special purposes.

For the purpose of lighting my burner I 50 have the following-described device: W is a can having a supply of alcohol or some similar fluid, and W' is a pipe provided with a suitable stop-cock (not shown) and leading to the annular depression W^2 in the perforated fire-plate $B B'$. By allowing a small quantity of alcohol or other similar fluid to flow into this depression and igniting it heat is generated about the pipe $C C' C^2$, and the contained oil is converted into vapor and 55 forced through the pipes $C^3 C^4$ to the orifices $E E' E E$ and after taking up the desired amount of air passes into the combustion-chamber S^3 , where it will become ignited and maintain an intense heat about the coil $C' C^2$, 60 and thus develop great heating power. In the meantime the starting-fire in the depression W^2 can be allowed to go out, as the 65

burner supplies its own generating power from the oil within the pipes as it flows from the source of supply, where it is kept under 70 some pressure or head.

The system of working this apparatus may be set forth as follows: The oil (kerosene) flows in through the pipe C and is heated in the coil $C' C^2$, so as to form a vapor which passes 75 down the pipe C^3 and is discharged from the pipe C^4 into the mixing apparatus in the sub-chamber. The mixture of air and vapor passes into the mixing-chambers $L L$ and M in the subchamber S and from there upward 80 through the openings in the plate $A^6 A^6$ into the concentric heating-chambers $S^1 S^2$, where it receives additional heat from the intense flame above the fire-plate $B B'$. Thence it passes through the perforations $D D D'$ into 85 the combustion-chamber $S^3 S^3$. By delivering the oil-vapor after it has been generated in the receptacle, through a series of small orifices and arranging in connection with each of these small orifices a needle-valve and a 90 separate group of air-injectors, each group embodying a primary nozzle and one or more secondary nozzles, as shown in Figs. 1 and 3, a larger quantity of oil may be vaporized, the vapor mixed with sufficient air and supplied to the combustion-chamber than can be done by any devise now in use. This 95 division of the oil-vapor by a series of orifices and connecting with each orifice groups of air-injectors is an essential feature of my 100 apparatus and gives it an advantage over any known device, inasmuch that the relative proportion of air to the oil-vapor will remain nearly constant regardless of the total amount of vapor and air supplied to the 105 combustion-chamber.

I claim—

1. In apparatus of the character described, a main burner and an auxiliary burner, each adapted to receive a separate supply of vapor 110 and air, an oil-vaporizing receptacle adapted to receive a supply of oil or hydrocarbon and to furnish a supply of vapor to each of the burners, said vaporizing-receptacle arranged to receive the direct heat of the flame from 115 the auxiliary burner, means to effect the supply of air to said main burner in the form of a plurality of fine jets, a group of injector-nozzles communicating with said main burner and adapted to coöperate respectively with 120 each of said plurality of jets, to furnish a supply of air to said burners, means whereby the amount of vapor supplied to each burner, and the amount of vapor supplied by each of the jets may be adjusted relatively to each other, 125 and means whereby the amount of vapor supplied to each burner may be regulated and the supply to the main burner cut off, while the supply of the auxiliary burner is maintained, substantially as set forth.

2. In an oil-burner, a combustion-chamber having an oil-supply pipe adapted to be heated in said chamber, a series or group of conical injector-nozzles, arranged in alinement,

said oil-supply pipe adapted to deliver its vaporized oil to said nozzles, concentric heating-chambers each adapted to receive a separate supply of mixed air and oil-vapor and 5 a perforated fire-plate between said heating-chambers and said combustion-chamber, substantially as set forth.

3. In apparatus of the character described, the combination of a vapor-supply pipe having jet-openings, needle-valves adapted to control the jet-openings of said pipe, a cross-bar connected to one of said needle-valves, a second cross-bar connected to the remainder of said needle-valves, a hand-lever, a right and 15 left hand screw-threaded rod connecting with said hand-lever, one of said cross-bars having screw-threaded connection with said rod and the other cross-bar having loose connection with said rod, substantially as set forth.

20 4. In apparatus of the character described, the combination of a vapor-supply pipe having jet-openings, needle-valves adapted to control the jet-openings of said pipe, a cross-bar connected to one of said needle-valves, a second cross-bar connected to the remainder of 25 said needle-valves, a head-piece, a hand-lever pivoted in said head-piece, guides secured to said second cross-bar for said first-referred-to cross-bar, a right and left hand screw-threaded rod having screw-threaded connection with said first-referred-to cross-bar and said head-piece, and a hand wheel or nut for actuating said rod, one of said cross-bars having loose connection with said rod, substantially as set forth.

35 5. In a hydrocarbon-burner, the combination of a combustion-chamber, a vapor-supply pipe having jet-openings, needle-valves for controlling jet-openings in said pipe, means 40 for actuating said valves, multiple series of conical nozzles receiving said needle-valves, those of each series being arranged in alignment with, and close to, each other, concentric heating-chambers communicating with 45 said combustion-chamber, a perforated fire-plate arranged between said heating-chambers and combustion-chamber, subchambers communicating with said heating-chambers, and centrally-contracted passages arranged 50 between said subchambers and said nozzles, substantially as set forth.

6. In a hydrocarbon-burner, the combination of a combustion-chamber having serially 55 perforated or apertured walls and centrally thereof an air-chamber with a register in its bottom, and a surrounding chamber also with a register in its bottom, a vapor-supply pipe with its coiled portion arranged in said combustion-chamber, a fire-plate adapted to admit a mixture of vapor and air into said combustion-chamber, heating-chambers arranged

below said fire-plate, and passages effecting communication between said vapor-supply pipe and said heating-chambers, substantially as set forth.

65

7. In apparatus of the character described, a main burner and an auxiliary burner, each adapted to receive a separate supply of vapor and air, an oil-vaporizing receptacle, adapted to receive a supply of oil or hydrocarbon, and 70 to furnish a supply of vapor to each burner, said vaporizing-receptacle arranged to receive the direct heat of the flame from the auxiliary burner, means whereby the supply of vapor to each burner may be regulated, and means 75 whereby, when the supply of vapor to the main burner is so regulated, the supply of vapor to said auxiliary burner will be simultaneously regulated, substantially as set forth.

8. In apparatus of the character described, 80 a main burner and an auxiliary burner, each adapted to receive a separate supply of vapor and air, an oil-vaporizing receptacle, adapted to receive a supply of oil or hydrocarbon, and 85 to furnish a supply of vapor to each burner, said vaporizing-receptacle arranged to receive the direct heat of the flame from the auxiliary burner, means whereby the supply of vapor to each burner may be regulated independently of the oil-supply, and means whereby, 90 when the supply of vapor to said main burner is increased, the supply of vapor to said auxiliary burner will be simultaneously increased a predetermined amount, substantially as set forth.

95

9. In apparatus of the character described, a main burner and an auxiliary burner, each adapted to receive a separate supply of vapor and air, an oil-vaporizing tube, or receptacle, adapted to receive a supply of oil and to furnish a supply of vapor to each burner, said 100 vaporizing-tube arranged to receive the direct heat of the flame from the auxiliary burner, means whereby the supply of vapor to each burner may be regulated, means whereby, 105 when the supply of vapor to said main burner is increased, the supply of vapor to said auxiliary burner will be simultaneously increased, means whereby, when the supply of vapor to said main burner is so increased or regulated, 110 the supply of vapor to said auxiliary burner is proportionally regulated, to maintain said vaporizing-tube at an approximately uniform temperature, substantially as set forth.

In testimony whereof I have signed my 115 name to this specification, in the presence of two subscribing witnesses, on this 25th day of September, A. D. 1900.

GEORGE L. BADGER.
